C. G. HOLMSTROM.
APPARATUS FOR MASSAGE AND THERAPEUTIC GYMNAStic TREATMENT.
APPLICATION FILED MAY 7, 1921.

1,400,547.

Patented Dec. 20, 1921.

Inventor:
Carl G. Holmstrom

UNITED STATES PATENT OFFICE.

CARL G. HOLMSTROM, OF WASHINGTON, DISTRICT OF COLUMBIA.

APPARATUS FOR MASSAGE AND THERAPEUTIC GYMNASTIC TREATMENT.

1,400,547.

Specification of Letters Patent. Patented Dec. 20, 1921.

Application filed May 7, 1921. Serial No. 487,541.

To all whom it may concern:

Be it known that I, CARL G. HOLMSTROM, residing at 10 Tenth street, northeast, Washington, D. C., a citizen of the United States, 5 have invented certain new and useful Improvements in Apparatus for Massage and Therapeutic Gymnastic Treatments, of which the following is a specification.

My invention relates to improvements in 10 massaging devices and has reference more particularly to a novel device for effectively massaging the legs and arms by a series of rollers movable around the limb.

The object of the invention is to provide 15 an extremely simple and inexpensive, yet a durable and efficient limb massager consisting primarily of a pair of frames curved for fitting around the limb and each provided with a series of parallel rollers, means 20 being provided for holding the frames in operative position around the leg or arm while they are jointly oscillated to cause the rollers to roll the flesh to and fro with any desired degree of pressure, which is preferably controlled by more or less forcible 25 pressure exerted by the hand of the operator.

With the foregoing in view, the invention resides in the novel subject matter herein- 30 after described and claimed, and illustrated in the accompanying drawing which depicts the preferred form of construction.

Figure 1 is a side elevation of a massaging device constructed in accordance with 35 the invention.

Fig. 2 is a plan view.

Fig. 3 is a sectional view, partly in elevation on line 3—3 of Fig. 2.

Fig. 4 is an elevation of a different form 40 of roller which may be used.

In the drawings above briefly described, the numerals 1 designate a pair of open rectangular frames which are carried by the front ends of a pair of handles 2 whose rear 45 ends are connected by a coiled spring 3, said frames, handles and spring being by preference formed from a single length of spring wire as shown.

The frames 1 each carry a series of parallel elongated massaging rollers 4 which may be of the plain form shown in Figs. 1, 2 and 3, corrugated as in Fig. 4, or of any other desirable design. The frames 1 are oppositely bowed in approximate conformity

with the transverse curvature of a human limb and it thus follows that when the affected limb is received between said frames and they are forced toward each other by pressing the handles 2 inwardly, the rollers 4 will be held against the limb with any desired amount of pressure, such pressure being under full control of the operator simply by increasing or decreasing the pressure on the handles with the hand holding them. By means of these handles, the entire 60 device may be oscillated to roll the rollers 4 around the limb and produce the desired and beneficial rubbing or massaging action. Furthermore, if desired, massage by pressure without any rubbing action, may be 65 done with the device by successively pressing the handles inwardly and releasing them. As soon as the handles are released they are separated by the spring 3 in readiness for their next operation, making the 70 device exceptionally easy and convenient to operate.

In any case of sluggish circulation, hardening of the arteries, stagnant tissues, etc., very beneficial results may be obtained and 75 proper blood action restored.

As excellent results may be obtained from the details disclosed, they are preferably followed, but within the scope of the invention as claimed, numerous minor changes may be 80 made and obviously any suitable materials 85 may be used.

I claim:

1. A massage device comprising opposed oppositely bowed frames substantially con- 90 forming in curvature to the transverse curvature of a human limb and adapted to receive a limb therebetween, similarly curved rows of parallel massaging rollers carried by said frames and adapted to be rolled 95 around the limb, and means whereby said frames may be held closed around the limb and jointly moved to operate said rollers.

2. A structure as specified in claim 1, said means consisting of a pair of self-separating 100 handles extending from said frames at an angle to the roller axes, the outer ends of said handles being yieldably connected with each other.

3. A massage device comprising opposed 105 oppositely bowed frames substantially con- forming in curvature to the transverse curvature of a human limb and adapted to

receive a limb therebetween, similarly curved rows of parallel massaging rollers carried by said frames and adapted to be rolled around the limb, a pair of handles extending 5 from said frames at an angle to the roller axes, and a coiled spring connecting the outer ends of said handles and serving to normally separate said handles; said frames, said handles and said spring being formed from a single length of spring wire. ¹⁰
In testimony whereof I have hereunto set my hand.

CARL G. HOLMSTROM.
